UNITED STATES PATENT OFFICE.

CHARLES J. COOPER, OF MOLINE, ILLINOIS, ASSIGNOR OF ONE-HALF TO H. W. COOPER
SADDLERY HARDWARE MFG. COMPANY, OF MOLINE, ILLINOIS, A CORPORATION
OF ILLINOIS.

CHAIN-COCKEYE.

1,307,436.

Specification of Letters Patent. Patented June 24, 1919.

Application filed December 22, 1917. Serial No. 208,368.

To all whom it may concern:

Be it known that I, CHARLES J. COOPER, a citizen of the United States, residing at Moline, in the county of Rock Island and State 5 of Illinois, have invented certain new and useful Improvements in Chain-Cockeyes, of which the following is a specification.

My invention relates to improvements in chain cock-eyes such as are used in connection with harness, and the object of the invention is to provide a cock-eye so constructed as to prevent displacement of the chain or links, thereby obviating damage to the leather or other parts of the harness, 10 while at the same time the construction is such as to allow of the insertion or removal of the chain link engaging the eye of the cock-eye.

The cock-eyes which have heretofore been 20 brought to my attention are of two kinds: First, those in which the eye of the cock-eye permits free play of the chain link, which results in damage to the leather of the trace, by reason of the end link of the chain striking against the leather loop surrounding the shackle of the cock-eye; and second, that type of cock-eye in which the eye is completely closed. In the latter type, the closed eye prevents damage to the leather, but it is 25 impossible to detach the link from the cock-eye when it is desired to use a chain of different length or repair an old chain.

My invention is designed to embody all of the advantages of the other types of 30 cock-eye and to be subject to none of the disadvantages of either type.

A specific embodiment of my invention is illustrated in the accompanying drawings, in which—

40 Figure 1 is an elevation of a chain cock-eye constructed according to my invention, together with the parts associated therewith;

Fig. 2 is a section taken on the line 2—2 of Fig. 1;

Fig. 3 is a perspective view of the principal part of the cock-eye; and

Fig. 4 is a modified form of pin for the cock-eye.

50 Referring to the drawings, 10, represents the end of the leather trace which, as is usual, is looped around the metal sleeve 11 which surrounds the cock-eye pin or bolt 12. The said pin or bolt 12, as illustrated

in Fig. 1, comprises a flat-head screw 55 which extends between the arms or limbs 13 and 14 of the cock-eye, and is threaded into the end of the limb 14, as shown at 15 in Fig. 1.

The cock-eye itself constitutes a connection between the trace 10 and the usual chain 16, the other end of the said chain being engaged with a suitable hook on the whiffle tree. The end link 17 of said chain is passed through the eye 18 situated at and 65 forming a part of the junction of the ends of the limbs 13 and 14 of the cock-eye.

The eye 18 is large enough to permit the proper amount of play or movement of the end of the link 17, but, as shown, the open 70 ends 19 and 20 of the eye are brought together, as shown in Fig. 1 at 21, the distance across the gap 21 being small enough to prevent the end of the link 17 from passing out of the eye 18 of the cock-eye. Hence it 75 will be seen that there is no possibility of the end of the trace 10 being damaged by the end of the chain.

In order to facilitate the insertion of the end link 17 into the eye 18 of the cock-eye, 80 the shackle bolt 12 is of course removable, in addition to which, at an intermediate point in its length, the link 17 is reduced in cross-section by flattening or otherwise, as indicated at 22 in Fig. 2. Such flattening allows 85 the link 17 to be manipulated in an obvious manner so that it may pass out through the narrow gap 21 at the open end of the eye 18 of the cock-eye.

The described construction effects a substantial saving in metal over those types of prior constructions hereinbefore referred to.

Fig. 4 illustrates a shackle pin in the form of a square-head bolt and nut which may be used, if desired, in place of the flat-head 95 pin 12 illustrated in Figs. 1 and 2.

The scope of the invention should be determined by reference to the appended claims.

I claim—

1. In combination, a chain cock-eye comprising a pair of separated limbs connected at one end to form an open-ended eye, the opening to which is of substantially less width than the interior width of the eye, a removable member connecting the opposite ends of said limbs, and a chain link having an endless metallic band having one of its

- ends engaged in said eye with a loose fit therein, the opening to said eye being of less width than the thickness of that portion of the link engaged in the eye, whereby the 5 said chain link is securely locked within the eye, said link having another portion of less width than the width of said opening, whereby, by suitably manipulating the link, it may be disengaged from said eye.
- 10 2. In combination, a chain having an end link of conventional oval shape, constructed of metal of circular cross-section, one side of said link having the metal thereof re-

duced in thickness, a chain cock-eye comprising a pair of separated limbs connected 15 integrally at one of their ends to form a partially closed eye in which said link is engaged, the opening to which is of less width than the diameter of the metal comprising the link but of greater width than 20 the thickness of the reduced portion of said link, and a removable pin extending between and connecting together the opposite ends of the cock-eye.

CHARLES J. COOPER.
